SOLIDIFIED NORMALLY LIQUID
SUBSTANCES

Simon Jacobowitz, Berlin-Charlottenburg, Germany, assignor to Gustav Snoek, Berlin, Germany, a corporation of Germany

No Drawing. Application November 5, 1937, Serial No. 172,922. In Germany November 17, 1936

3 Claims. (Cl. 167—63)

This invention relates to a process for solidifying normally liquid substances, such as liquid polyhydric alcohols, and to the solidified products obtained thereby.

5 It has been proposed to solidify glycerine by an addition of sodium stearate, or soap made from hard fats, in association, if desired, with other agents. Glycerine thus solidified may also be worked up into lubricants, anti-friction agents, 10 salves, or the like. Naturally, owing to their content of soap, such products have an alkaline reaction which, as is well known, is undesirable in many instances. Moreover, the purpose for which they are to be used precludes the additional use of agents with an acid reaction, such as salicylic acid or the like. Again, the addition of substances, such as zinc oxide, which react with soap, is usually impossible.

It has now been found that saturated fatty alcohols of the group C₈—C₁₈, for example myristyl-, palmityl-, docosyl- and myricyl alcohol, or technical mixtures of same, are adapted to solidify glycerine and glycol respectively.

This action may exactly be controlled by the joint use of chemical compounds of saponaceous character, such as salts of the sulphuric acid esters of fatty alcohols, or of fatty-acid condensation products, or the like. Depending on the relative proportions of the substances employed, 30 the resulting products are similar to "Vaseline", or also opaque salves and lubricants. Nearly solid preparations can also be obtained with the agents specified.

In order to distribute these alcohols in the most suitable manner in the glycerine and glycol respectively, the joint use of known emulgents, i. e. emulsifying and dispersingly acting substances, which do not have an alkaline reaction in an aqueous solution, is recommended. Such 40 substances are first of all the neutralization products of sulphuric acid esters

(a) Of fatty alcohols, i. e. of higher molecular aliphatic alcohols with at least 8 carbon atoms and

45 (b) Of mono- and di-glycerides respectively of higher molecular fatty acids.

For many purposes the neutralization products of sulphurated unsaturated mineral oils, sulphurated castor oils, sulphurated fatty acids of 50 castor oils, sulphurated fatty acids of fish oil also may be used.

Finally those fatty acid condensation products represent excellent emulgents which are obtained by condensing higher molecular fatty acids in 55 the form of their haloids with the most various

water soluble organic products, for instance, the sulphuric acid esters of low molecular oxyalkylamines, as aminoethyl-sulphuric acid, or the oxy- and aminoalkyl-acid sulphides respectively, for example, oxyethan- acid sulphide or aminoethan- acid sulphide, or the decomposition products of albumen as for instance lysalbic acid.

5 Gelatinous preparations, applicable with advantage as lubricants and anti-friction agents for technical purposes, can be produced in extensive 10 variety.

The joint employment of skin emollients, such as salicylic acid or the like, and also of anti-corrosive agents in the case of preparations used as lubricants for special purposes in the ma- 15 chinery industry, is also easily possible.

The present process enables the products to be adapted to meet the chief physical properties required for their technical application, such as the consistency which is retained even at low 20 temperatures, by judicious selection of different ingredients and their proportions in the mixture.

Finally, the resulting products, both as such, and also after the addition of fillers such as starch, agar-agar, dimethylcellulose, and the like, or substances with a medicinal or cosmetic action, form valuable preparations for the care 25 of the skin or for pharmaceutical purposes.

In addition to glycerine, the so-called glycerine substitutes, such as glycols (ethylene-, butylene- 30 and pentamethylene glycols) aqueous sugar solutions, and the like, may also be solidified by the present process. Glycerine and glycols can be used both in the anhydrous form and diluted with water. The products obtained by the process 35 of the invention may be arranged to have an acid, neutral, or alkaline reaction.

The following examples will serve to illustrate the invention.

Example I

40

50 parts by weight of sugar are dissolved in 40 parts by weight of water, and 9 parts by weight of cetyl alcohol, together with 1 part by weight of the sodium salt of stearyllysalbic acid, are stirred into the warm solution. On continuing 45 to stir the mixture till cold, an unctuous mass, suitable for many purposes, is obtained.

Example II

50

9 parts by weight of myristyl alcohol are melted down, with 90 parts by weight of anhydrous glycerine, on the water bath, and 1 part by weight of sodium cetyl-sulphate and 10 parts by weight of starch are stirred in. The stirring of the mass 55 is continued until cold, a semi-solid, unctuous

mass, forming a good medium for the care of the skin, being obtained.

Example III

5 8 parts by weight of a technical mixture consisting of approximately equal parts of palmityl- and stearyl alcohol, are melted down on the water bath with 2 parts by weight of triethanolamine dodecylphosphate and 80 parts by weight of hydrated (80%) glycerine, and treated with 2 parts by weight of salicylic acid, the whole being stirred until cold. An excellent agent for the pediculure is obtained.

What I claim is:

15 1. A solid composition of matter comprising a substance selected from the group consisting of glycerine, glycols, and aqueous sugar solutions, in combination with a neutralization product of

a sulphuric acid ester of a fatty alcohol having at least 8 carbon atoms in admixture with myristyl alcohol, said mixture being in an amount sufficient to solidify said substance.

2. A solid composition of matter comprising a substance selected from the group consisting of glycerine, glycols, and aqueous sugar solutions, in combination with sodium cetyl sulphate in admixture with myristyl alcohol, said mixture being in an amount sufficient to solidify said substance. 5

3. A solid composition of matter comprising a substance selected from the group consisting of glycerine, glycols, and aqueous sugar solutions, in combination with about 8-10% myristyl alcohol and 1-2% of a neutralization product of a sulphuric acid ester of a fatty alcohol having at least 8 carbon atoms. 15

SIMON JACOBOWITZ.
